BOOKBINDING APPARATUS

Milton Berlanstein, Brooklyn, N. Y.

Application May 20, 1939, Serial No. 274,816

14 Claims. (Cl. 11—1)

The object of my invention is to provide a simple, portable and inexpensive apparatus, particularly adapted for use by students or amateurs, in schools, in shops, in print shops, and elsewhere.

A further object of my invention is to provide a bookbinding apparatus which is a complete unit in that all the ordinary processes and operations of bookbinding and book repairing can be carried out with it; which processes and operations include drilling, side stitching, saddle stitching, backing, trimming, pressing, stamping, etc., and to permit the performing of these processes and operations for any type of bookbinding work, as for example books consisting of various signatures, magazines, loose sheets etc.

This invention pertains more especially among other things to (A) the two clamping or pressing boards forming the nucleus for the unit and to the assembly of these boards by means of bolts and wing nuts; (B) to the use of coil springs which elevate the top board when pressure is removed by loosening the wing nuts thus facilitating insertion of sheets or signatures between the boards; (C) to the device for setting up cords or tapes for saddle stitching; (D) to the device for clamping the material preparatory for drilling for the purpose of side stitching; (E) to the jogging plate for holding the leaves of the book in the proper position preparatory to clamping and drilling and similarly for holding properly same in a different position for the purpose of side stitching; (F) to the device for backing books; and (G) to the adjustable cutting plow which slides across the front of the press and trims off the edge of the book that is protruding from between the press boards.

My invention and improvements are further explained by references to the accompanying drawings, in which:

Fig. 1 is a plan view of my bookbinding apparatus;

Fig. 2 is a front view and

Fig. 3 is a side view thereof;

Fig. 4 is a perspective view of the apparatus and is shown together with the jogging guide and the trimmer mounted on it;

Fig. 5 is a sectional detail of the drilling clamp;

Fig. 6 is a detail showing of the trimmer in operation;

Fig. 7 is a face view of the trimmer unit;

Fig. 8 is a detail showing of a portion thereof;

Fig. 9 is a detail showing of the jogging guide mounted on the press and

Fig. 10 is a perspective view of the jogging guide.

Like parts are identified by the same reference numerals throughout the several views.

The press portion of the unit consists of two identically sized hard wood boards 20, 21 with bolts 22 passing through the two boards a short distance in from the corners. At the bottom of the board 20 are two cleats 23 that run along the end of the bottom and are secured to the board by wood screws. The bolts 22 pass through the cleats as well as the boards. The holes in board 20, through which bolts pass, are enlarged to admit coil springs 24. The holes are drilled to a depth where, when coil springs 24 are completely compressed, they will fit completely into the holes and not protrude above the top face of the board. If necessary these enlarged holes may be drilled down into cleats but must not go through them. When wing nuts 25, 26 are screwed back up on bolts the springs force board 21 up and hold it in raised position until wing nuts are again screwed down. Metal strips 27 are set in the ends of board 21 to prevent warping, bending and cracking. The back edges of the boards are cut at an angle as shown and also have secured to them band metal strips 28. In the front edge of board 20 is cut a rabbet 29. The remainder of the front edge of board 20 is covered by a reinforcing metal strip 30 which has a rounded upper edge that protrudes slightly above the inside face of board 20. Running along the bottom edge of rabbet 29 and closing said rabbet on the third side is metal strip 31 affixed to the lower face of the board by screws. It is in this groove 29 that the plow rides when trimming as shown in Fig. 4. More will be said of this plow later in the description. Completely covering the front edge of the board 21 is the metal strip 32 that is secured in place by wood screws and has its upper edge flush with the outside face of board and has its inside edge rounded and slightly protruding below the inside face of board. A short distance in from each end of strip 32 are two tapped holes to admit thumb screws 33. Thumb screws serve to hold the tape securer 34 in place. The tape securer 34 runs along the front edge of board 21 and is made of the same type of wood as the boards are made of. The upper edge of the tape securer 34 is flush with the top face of the board 21 and the top edge of the metal strip 32, but the bottom edge of the tape securer is set well back from the bottom edge of the metal strip. Thumb screws 33 pass

through the tape securer and screw into tapped holes in metal strip 32.

The press is held securely in a horizontal position to a table, bench etc. by four suction cups 35. The upper portion of the suction cups fit over the heads of the bolts and are held in place in that manner.

The drilling clamp consists of the two main parts, 36 and 37. The bottom part 37 is a strip 10 of iron or other suitable metal that has two holes drilled in it to allow bolts 22 to pass through it. On each end of the strip 37, there are three projecting pins 38, 39, 40. These pins are to hold the jogging guide 50 in place. More will be said of 15 this guide later. The top part 36 of the drilling clamp consists of an iron casting of the same length and width as the lower part 37 and has its lower surface machined. The part 37 has two holes in it to allow bolts 22 to pass through it in 20 the same relative place as they pass through the lower part. The top part 37 also has enlarged holes in it about the bolts 22 to admit coil springs 41. These coil springs 41 force the upper part 36 of the drilling clamp to rise when wing nuts 25 are unscrewed. The coil springs 41 used on 25 the drilling clamp are much weaker than the four coil springs 24 that are used to raise the upper board of the press. The top part of the drilling clamp has holes 42 at a slight distance in from 30 the edge and suitably spaced from each other, these serving as guides for the convenient drilling of a book when the table or side stitch method is employed. Holes 43 in the lower part of the drilling clamp are directly below the holes 42 but 35 are a little larger and are also countersunk on the inner end of the hole. Both holes 42 and 43 are in that part of the drilling clamp that extends over the back edge of board 21. 44 and 45 are guides against which the ends of the papers or 40 signatures, that are placed in the drilling clamps, are jogged. The guide 44 is a round piece of metal that screws into the lower part 37 of the drilling clamp and passes through a hole in the upper part 36 of the drilling clamp. The guide 45 45 is a wooden dowel that is held by friction in a hole in the board 21. The guide 45 is directly in line with guide 44.

The saddle stitching frame is disposed at the front of the unit and consists of the upper tape securer 46 which is made of the same kind of wood as the boards are made of, and has two holes in it to allow bolts 22 to pass through it, and also has an elongated opening 47 cut in it. The upper tape securer 46 rests on nuts and washers 48. 50 When the strip 46 is in the desired position it is locked in place by tightening down washers and nuts 49. The opening 47, which is directly above the lower tape securer 34 and is as wide as the lower tape securer, has a series of removable pegs 60 60 in it. A wooden dowel 61 is held by friction in a hole in the upper board and passes through a hole in upper tape securer 46 and is used to jog signatures against when they are placed in the saddle stitching frame.

65 The plow for trimming consists of the heavy element 51 which has attached to it on its bottom edge the cutting blade which is held in place by beveled piece 53 and metal screw 54. The two guide rods 55 screw into the element 51 and are 70 secured in that manner. The jack screw 56 passes through the element 51. The portion of the jack screw 56 that passes through the element 51 is slightly reduced in diameter. The plate 57 has two holes in it for the guide rods 55 to pass 75 through and has a tapped hole in it to fit jack

screw 56. The plate 57 is rabbeted thus providing a shouldered portion 58 which enters the groove 29 in the board 28. Thumb screw 58 is attached to the jack screw by a rivet. The two tubes 59 are carried by the guides 55 and serve to prevent 5 the plate 57 from being drawn up against the blade 52 and in that way ruining its keen edge.

The jogging guide 50 seen in Fig. 10 is made of stamped sheet iron. It has a few openings 50' in its front to enable one to see the material while 10 it is being forced against it. It has notches 62, 63, 64 in the bottom of its side walls 65 that fit over pegs 38, 39, and 40 on the ends of the lower plate 37 of the drilling clamp when the jogging 15 guide 50 is set in place.

The adjustments that have to be made on the unit for the many operations involved in the binding or repairing of a book are a simple few as can be seen from the following. To further the ease of understanding the versatility of my unit 20 I shall describe all the operations necessary for the complete binding of a book on my unit by both the side and saddle stitch methods.

How side stitching is done on my unit (assuming the unit to be as in Fig. 3).—Loosen wing nuts 25 25 and plate of the drilling clamp will be forced up by springs 41. Now place jogging guide 50 in place for drilling on the front of the drilling clamp by bringing notches 62, 63, 64 in engagement with pegs 38, 39 and 40. Papers or signatures that are 30 to be bound are placed in the drilling clamp. When putting the papers or signatures in the drilling clamp, jog the ends of the material against guides 44, 45 and jog the edge at right angles to the end against the jogging 35 guide 50. The openings 50' in jogging guide 50 will enable you to see whether all the material in the drilling clamp is set properly before it is clamped for drilling. Tighten down wing nuts 25 40 clamping the material between the two parts of 40 the drilling clamp. By now drilling down through holes 42, with a twist drill of the same diameter as that of holes, until the drill can be seen on the under side of the lower portion of the drilling clamp, holes will be made in the material that is 45 clamped in the drilling clamps that will be of the proper diameter and be the proper distance in from the edge for best results in side stitching. The jogging guide 50 is now moved back by placing notches 62 over pegs 39 which will again bring 50 notches 64 over pegs 40. The wing nuts 25 are now loosened and the material in the drilling clamp, that has just been drilled is moved forward until it is again against the jogging frame 55. The wing nuts 25 are again tightened; the 55 guide 50 is removed and the material sewn.

To trim the book on my unit (assuming the unit to be as in Fig. 3).—Remove the tape securer 34 by unscrewing thumb screws 33. Loosen wing nuts 25, 26 until board 21 is raised by coil springs 60 24 to a point that will admit the material 66 you wish to trim, between the boards 20 and 21. Place the material 66 between boards with the waste you wish to trim off protruding out beyond the metal strip 30, 32 on the front edge. Insert cutting 65 board 67 between the material to be trimmed and board 20 in the position shown. Tighten down wing nuts 25, 26 until they will go no further. Stand the press on the edges 28. The cutting plow is then placed over the upper edge by inserting 70 the shouldered portion 58 into groove 29 and twisting thumb screw 58 until the point of the blade just touches the material to be removed. Draw the plow along to a point where it has passed the material to be removed and give the thumb screw 75

a twist to draw the blade in a bit. Now draw the plow across the front of the press keeping the part 58 in groove 29. This will bring the blade 52 across the protruding material of 66 and cut part 5 of it away. Now twist the thumb screw 58 again to draw blade in and come back across the front of the press. Continue this until all the protruding waste is removed.

To back a book on my unit (assuming the unit 10 to be as in Fig. 3).—Remove the lower tape holder 34 as described above. Clamp the material to be backed between the boards with the edge to be backed protruding beyond backing irons 28. Stand the press up so it rests on its 15 front, that is it rests on iron pieces 30 and 32. The material is now being held in a convenient position to be rounded and backed.

How pressing is done on my unit (assuming the unit to be as in Fig. 3).—When the cover has glue 20 on it and is placed on contents, clamp it between boards, having the projecting edges of metal strip 30, 32 fit into the hinge of the book cover. By screwing down wing nuts 25, 26 the two boards are forced together. When the book is in pressing 25 position all that is necessary is to stand the unit up on the back end so it rests on the edges 28 and the book is in position to be lettered on its back.

How saddle stitching is done on my unit (Assuming the unit to be as in Fig. 3).—Cut the desired 30 number of tapes to size. Loosen lower tape holder by unscrewing the thumb screws 33. Place the bottom of the tapes between wooden strip 34 and metal strip 32 by tightening thumb 35 screw 33. Remove pegs 60 from opening. Bring the upper ends of the tapes, through opening 47 and after drawing each one tight wedge it in place by forcing a peg 60 in next to it. When all the necessary tapes are in place they may be 40 tightened by screwing up nuts 48.

While I have described more or less precisely the details of construction, I do not wish to be understood as limiting myself thereto, as I contemplate changes in form and the proportion of 45 parts and the substitution of equivalents and circumstances may suggest or render expedient without departing from the spirit or scope of my invention.

Having thus described my invention, I claim: 50 1. A bookbinding apparatus comprising: a pair of boards forming a press, a threaded bolt passing through each corner of said press; a tape holder associated therewith and comprising a clamping strip removably carried by an edge of 55 a board of the press, for holding one end of the tapes, a second cooperating tape holder carried by one pair of said bolts for holding the other end of the tapes, said second holder having a longitudinal slot to receive the ends of the tapes 60 and wedges to hold said tapes in said slot.

2. A bookbinding apparatus comprising a pair of superposed boards forming a press, a threaded bolt passing through each corner of said press and extending substantially beyond the upper 65 board, helical springs disposed between said boards and surrounding said bolts to hold said boards in spaced relation, nuts on said bolts operable to close said boards against the action of the springs, a tape holder carried by the protruding 70 portions of one pair of said bolts, and a drill guide carried by the protruding portions of another pair of said bolts.

3. A bookbinding apparatus comprising a pair of superposed boards forming a press, a threaded 75 bolt passing through each corner of said press

and extending substantially beyond the upper board, helical springs disposed between said boards and surrounding said bolts to hold said boards in spaced relation, nuts on said bolts operable to close said boards against the action of the 5 springs, a tape holder carried by the protruding portions of one pair of said bolts, and a drill guide carried by the protruding portions of another pair of said bolts, said drill guide comprising a pair of narrow plates carried by said 10 bolts, spring means for holding said plates in any desired spaced relation to permit the introduction of work between the plates, said plates each having a series of holes equally spaced from the edge of the plate to serve as drill guides. 15

4. A bookbinding apparatus comprising a pair of superposed boards forming a press, a threaded bolt passing through each corner of said press and extending substantially beyond the upper 20 board, helical springs disposed between said boards and surrounding said bolts to hold said boards in spaced relation, nuts on said bolts operable to close said boards against the action of the springs, a tape holder carried by the protruding portions of one pair of said bolts, and a 25 drill guide carried by the protruding portions of another pair of said bolts, one pair of superposed edges of the boards being beveled and faced with backing plates to permit the backing of a book held in said press, another edge of the lower 30 board being grooved to carry a cutter to trim a book.

5. A jogging guide comprising a plate having a plurality of window openings thereon and an end 35 wall projecting forwardly from each end of said plate, each end wall having notches in its lower edges.

6. A bookbinding apparatus comprising a pair of superposed boards forming a press and having bolts passing through said boards to hold the 40 same in assembled relation and also having springs interposed between the boards to hold the same yieldingly in any desired spaced relationship to permit the free introduction of work 45 between the boards; a tape holder associated with the upper board of the press along one edge and comprising a bar carried by one pair of said bolts and spaced from the board, the bar having a longitudinal slot in substantial registry with the 50 edge of the board, wedges to hold one end of the tapes in the slot and a removable clamp operating against the edge of the upper board to clamp the lower ends of the tapes; a drill guide carried by another pair of said bolts and comprising a pair of superposed clamping plates having drill holes 55 in registry, and a removable jogging guide carried by said drill guide.

7. A bookbinding apparatus comprising a pair of superposed boards forming a press and having bolts passing through said boards to hold the 60 same in assembled relation and also having springs interposed between the boards to hold the same yieldingly in any desired spaced relationship to permit the free introduction of work 65 between the boards, said boards having at one edge a pair of ribs projecting toward each other and cooperating to press the hinge of a book; a tape holder associated with the upper board of the press and along the same edge and comprising a bar carried by one pair of said bolts and spaced from the board, the bar having a longitudinal slot in substantial registry with the edge 70 of the board, wedges to hold one end of the tapes in the slot and a removable clamp operating against the edge of the upper board to clamp 75

- the lower ends of the tapes, and a drill guide carried by another pair of said bolts and comprising a pair of superposed clamping plates having drill holes in registry.
5. 8. A bookbinding apparatus comprising a pair of superposed boards forming a press and having bolts passing through said boards to hold the same in assembled relation and also having springs interposed between the boards to hold 10 the same yieldingly in any desired spaced relationship to permit the free introduction of work between the boards, said boards having at one edge a pair of ribs projecting toward each other and cooperating to press the hinge of a book;
- 15 9. a tape holder associated with the upper board of the press and along the same edge and comprising a bar carried by one pair of said bolts and spaced from the board, the bar having a longitudinal slot in substantial registry with the 20 edge of the board, wedges to hold one end of the tapes in the slot and a removable clamp operating against the edge of the upper board to clamp the lower ends of the tapes, a drill guide carried by another pair of said bolts and comprising a pair of superposed clamping plates 25 having drill holes in registry, and a removable jogging guide carried by said drill guide.
10. A bookbinding apparatus comprising a pair of superposed boards forming a press and having bolts passing through said boards to hold the same in assembled relation and also having springs interposed between the boards to hold the same yieldingly in any desired spaced relationship to permit the free introduction of work 30 between the boards, said boards having at one edge a pair of ribs projecting toward each other and cooperating to press the hinge of a book; a tape holder associated with the upper board of the press and along the same edge and comprising a bar carried by one pair of said bolts and spaced from the press, the bar having a longitudinal slot in substantial registry with the 35 edge of the board, wedges to hold one end of the tapes in the slot and a removable clamp operating against the edge of the upper board to clamp the lower ends of the tapes, a drill guide carried by another pair of said bolts and comprising a pair of superposed clamping plates 40 having drill holes in registry, and a removable jogging guide carried by said drill guide, another edge of the lower board being formed with a longitudinal groove; and a cutter unit slidable in the said groove and operable to trim the edge of the work held in the clamp.
11. A bookbinding apparatus comprising a pair of superposed boards forming a press, a threaded bolt passing through each corner of 45 said press and extending substantially beyond the upper board, a tape holder carried by the protruding portions of one pair of said bolts, and a drill guide carried by the protruding portions of another pair of said bolts.
12. A bookbinding apparatus comprising a pair of superposed boards forming a press, a threaded bolt passing through each corner of 50 said press and extending substantially beyond the upper board, and a drill guide carried by the protruding portions of a pair of said bolts, said drill guide comprising a pair of narrow plates carried by said bolts, spring means for holding said plates in any desired spaced relation to permit the introduction of work between the plates, said plates each having a series of holes 55 equally spaced from the edge of the plate to serve as drill guides.
13. A bookbinding apparatus comprising a pair of superposed boards forming a press, a threaded bolt passing through each corner of 60 said press and extending substantially beyond the upper board, and a drill guide carried by the protruding portions of a pair of said bolts, one pair of superposed edges of the boards being beveled and faced with backing plates to permit the backing of a book held in said press, another edge of the lower board being grooved 65 to carry a cutter to trim a book.
